(57) **CLAIM**

The ornamental design for a motor vehicle body as shown and described.

DESCRIPTION

FIG. 1 is a left, front perspective view of a motor vehicle body showing our new design;

FIG. 2 is a right, rear perspective view thereof;

FIG. 3 is a top plan view thereof;

FIG. 4 is a front elevation view thereof;

FIG. 5 is a rear elevation view thereof;

FIG. 6 is a right side elevation view thereof;

FIG. 7 is a left side elevation view thereof.

FIG. 8 is a front left perspective view of a vehicle according to another embodiment;

FIG. 9 is a rear right perspective view of the vehicle of FIG. 8;

FIG. 10 is a top plan view of the vehicle of FIG. 8;

FIG. 11 is a front elevation view of the vehicle of FIG. 8;

FIG. 12 is a rear elevation view of the vehicle of FIG. 8;

FIG. 13 is a right side elevation view of the vehicle of FIG. 8; and,

FIG. 14 is a left side elevation view of the vehicle of FIG. 8.
